(57) **CLAIM**

The ornamental design for a fixture element, as shown and described.

DESCRIPTION

In a preferred embodiment, the nature of this product is a fixture element in the form of a housing and/or housing and lens for a lighting device, such as a wall-mounted light fixture with a flexible support arm.

FIG. 1 is a right, top, front perspective view of a fixture element according to our new design;

FIG. 2 is a right side elevational view thereof, the left side elevational view thereof being a mirror image of the right side shown;

FIG. 3 is a top plan view thereof;

FIG. 4 is a bottom plan view thereof;

FIG. 5 is a front elevational view thereof; and,

FIG. 6 is a rear elevational view thereof.

The portions of the design shown in broken lines are shown for the purpose of illustrating environmental structures only and form no part of the claimed design. The broken lines immediately adjacent to the shaded surfaces represent boundary lines and form no part of the claimed design.
